SNUBBED BOLSTER TRUCK

Leo A. Lehrman, Chicago, Ill., assignor to American Steel Foundries, Chicago, Ill., a corporation of New Jersey

Application March 5, 1948, Serial No. 13,171

10 Claims. (Cl. 105—197)

1

This invention relates to railway car trucks and more particularly to an improvement on the structure shown in United States Letters Patent No. 2,378,414, Car Truck, issued on June 19, 1945, to David M. Light.

Expressed generally, the principal object of this invention is to provide in a railway car truck, friction means between the side frame and the bolster for damping the vertical movements of the bolster, said friction means comprising a friction shoe pocketed in a column of the side frame in slidable engagement with column wedge surfaces sloping toward said bolster, and a diagonally arranged spring reacting between said shoe and the compression member of the side frame for urging the shoe along said surfaces and into frictional engagement with said bolster.

A further object of the invention is to provide novel friction means of the type described wherein in the friction shoe and column wedge surfaces are arranged to engage each other at points aligned with the axis of the shoe-actuating spring transversely of the column whereby the resultant force exerted against the shoe is substantially uniformly distributed over the full friction face thereof, thus maintaining full face engagement between the shoe and the bolster.

Another object of the invention is to arrange the parts of the friction device in such a manner as to more effectively utilize the forces exerted by the shoe-actuating spring.

A still further object of the invention is to provide a friction assembly wherein the column wedge surfaces, the friction shoe wedge surfaces and the spring are cooperatively arranged to position the friction shoe in such manner that it normally tends to have the friction face thereof in full face engagement with the associated bolster friction surface and maintain said engagement during all movements of the bolster.

These and other objects of the invention will be apparent from the specification and the drawings, wherein:

Figure 1 is a fragmentary sectional view of a railway car truck embodying my invention, the section being taken in a longitudinal vertical plane substantially as indicated by line 1—1 of Figure 2, only one end of the truck being shown inasmuch as it is similar at opposite ends thereof;

Figure 2 is a sectional view taken in the transverse horizontal plane substantially as indicated by the line 2—2 of Figure 1;

Figure 3 is a further sectional view taken in the vertical plane substantially as represented by line 3—3 of Figure 1, the bolster, however, being

shown in phantom lines to more clearly illustrate the arrangement of the friction shoe and the column; and

Figure 4 is a perspective view of the friction shoe.

Describing the invention in detail, the truck frame comprises a compression member, generally designated 2, a tension member 4, and a column, generally indicated 6, adjacent each end 19 of the frame defining with said members a bolster opening 10 widened at its lower end as at 11 for a purpose hereinafter described. The tension member is of box section and comprises a widened top chord 12 with upstanding inboard and outboard spring-positioning flanges 14 and 16. The widened top chord 12 affords a seat as at 18 for a set of compression springs 20, 20, said springs providing a support for a bolster 24.

The bolster is of box section and comprises a bottom wall 26 seated as at 22 on said springs, said bottom wall being provided with the usual spring-retaining lugs 28, 28 confining the before-mentioned springs therebetween. The bolster also has a top wall 30, a side wall 32 at each side thereof, and a center rib 34. On the side walls of the bolster are provided the usual inboard and outboard interlocking lugs 36 and 38 which embrace the column 6 therebetween. It will be noted that the outboard guide lug is proportioned to fit through the widened portion 11 of the bolster opening to accommodate assembly and disassembly of the bolster with respect to the side frame in the conventional manner.

On each side wall of the bolster between the inboard and outboard interlocking lugs thereon 35 is mounted a substantially vertical friction plate 40 with upper and lower flanges 42, 42 recessed within the top and bottom of the bolster and embracing the bolster therebetween, thus interlocking the friction plate with the bolster. The friction plate may, of course, be welded or otherwise secured to the bolster to be part thereof. The friction plate 40 cooperates with a friction shoe 44 pocketed within the column 6 as hereinafter 45 more particularly described.

The friction shoe is of skeletal construction somewhat cup-shaped in form and comprises vertically diverging front and rear walls 46 and 48 and a bottom wall 50 angularly related to the horizontal plane of the bolster, that is, the plane of the bottom wall is at an oblique angle to the vertical plane of the friction plate 40 of the bolster as best seen in Figure 1. The front wall 46 of the friction shoe engages the friction plate 40 as at 51 on a substantially vertical plane.

3

The shoe also comprises side walls 52, 52, generally triangular in shape, said side walls interconnecting said front and rear walls 46 and 48. Each side wall 52 presents a diagonal or downwardly sloping crowned wedge surface 54 curved longitudinally thereof, these surfaces lying in a plane disposed at an acute angle with respect to and sloping toward the vertical friction surface on the friction plate of the bolster. It will be noted that the rear wall 48 of the shoe is arcuately formed intermediate its ends and is cored away to form the curved surface 49 to afford clearance for a compression spring 56 which extends into the shoe and seats at its lower end on a spring seat or abutment surface 58 on the bottom wall 50 of the shoe eccentrically of the central longitudinal median line of the shoe, that is, the spring is positioned adjacent the rear wall of the shoe. The spring is disposed so that its axis is at an acute angle to the vertical plane of the friction plate 40 of the bolster and normal to the spring seat surface 58 of the shoe. The lower end of the spring is positioned on said abutment surface 58 between surface 49 on the rear wall of the shoe and a reinforcing boss 59 formed with said bottom and front walls of the shoe at the juncture thereof. The upper end of the spring seats against an abutment or spring seat surface 60 on the compression member 2, said abutment surface being disposed in a plane substantially normal to the axis of said spring 56, or, in other words, substantially parallel to the spring seat surface 58 on the shoe. The abutment surface 60, in the present instance, is the undersurface of a tie web or wall 62 which connects the lower ends of the inboard and outboard webs 64 and 66 of the compression member, said inboard and outboard webs merging with a top web 68 of the compression member, the compression member being generally of inverted channel shape. One side of the upper end of the spring is positioned on the abutment surface 60 by means of a depending boss or lug 70 formed on said web 62 adjacent the bolster opening 10 and on its opposite side the spring is positioned by spaced transversely extending slightly inclined webs 72, 72 formed on the inner edges of the spaced inboard and outboard walls 74 and 76 of column 6, these edges being remote from the bolster opening.

The upper ends of walls 74 and 76 and webs 72, 72 merge with web 62 of the compression member, forming a pocket for the shoe at the upper end of the column, and the lower ends of webs 74 and 76 merge with the tension member. However, the lower ends of the webs 72, 72 terminate a short distance below the upper ends of walls 74 and 76 and merge with the inner ends of spaced coplanar ribs or ledges 78 formed on the inner or adjacent sides of walls 74 and 76 and sloping downwardly toward the bolster opening. The ledges 78 receive the shoe 44 therebetween and present on their upper sides substantially flat coplanar wedge surfaces 80, 80 sloping toward the bolster and lying in a plane substantially parallel to that of surfaces 54 on the lower ends of the side webs 52 of the shoe. The surfaces 54 and 80 engage each other tangentially (Figure 1), the engagement occurring between related surfaces 54 and 80 at a point 82, at the crest of surface 54, the points 82 being aligned with the axis of the spring transversely of the side frame. By locating the point of engagement between the shoe and the ledges in the plane of the axis of the spring, the shoe is normally held in the position

4

shown in Figure 1 with the friction surface of the shoe in flat face engagement with plate 40. This arrangement avoids any tendency on the part of the spring to cant the shoe, thus providing for a substantially uniform distribution of the forces exerted by the spring over the full friction face of the shoe so that even wear on the full face of the shoe and friction plate is effected. The shoe does not tend to have edge contact with the bolster friction plate. Due to the manner of engagement between surfaces 54 and 80, the shoe is capable of rocking within the column in accordance with the canting or angling movements of the bolster and/or side frame. In this connection it will be noted that the points of engagement 82, 82 between these surfaces are disposed much closer to the rear wall of the shoe than to the front or friction wall thereof. Inasmuch as the spring is positioned adjacent the rear wall of the shoe, it in effect seats at one side on the relatively short lever arm of the shoe, considering the points 82 as points of pivot. This feature, in addition to the fact that the axis of the spring is aligned with the point of pivot or fulcrum (points 82, 82) of the shoe, reduces to the minimum bending stresses on the spring during such rocking movement of the shoe, wherefore the life of the spring is considerably prolonged. In other words, the spring is seated on portions of the shoe which move much less than the friction surface of the shoe.

The lower end of column 6 is provided with a web 84 connecting the inboard and outboard webs 74 and 76 of the column 6 at the forward edges thereof defining the widened portion 11 of the bolster opening. The web 84 is cored away to form a substantially vertical slot 86 intermediate webs 74 and 76 to accommodate downward movement of the friction shoe, the slot dividing the upper end of web 86 into spaced legs 87, 87 merging with the forward ends of the ledges 78, 78.

The rear wall 48 of the shoe is offset to form a loop 88 which projects into an opening or slot 90 (Figure 3) defined between the webs 72, 72 of column 6. The loop 88 is designed to accommodate the insertion of a pin therethrough for abutment with the adjacent edges of webs 74 and 76 to lock the shoe in a retracted position in the column to facilitate assembly and disassembly of the bolster with respect to the side frame.

It will thus be apparent that the spring 56 is oriented to exert a force against the shoe 44 in a plane diagonal to the plane of the friction plate 40 on the bolster and that the spring 56 exerts a force substantially normal to the bottom wall 50 of the shoe and web 62 of the compression member, the surface 60 of the compression member and surface 58 on the shoe lying in substantially parallel planes disposed at an obtuse angle to the vertical plane of the friction plate 40. The spring 56 exerts a force on the shoe below the areas of engagement between surfaces 54 on the sides of the shoe and surfaces 80 on the ledges 78. It may also be noted that the transverse webs 72, 72 of the column are inclined from the vertical and substantially parallel to the plane of the adjacent portions of the rear wall 48 of the shoe, thus affording a clearance for the rear wall of the shoe to accommodate movement of the shoe into the column upon lateral movement of the bolster 24 toward the shoe. The rear wall of the shoe and the webs 72, 72 are adapted to engage each other along generous bearing areas at a locking

angle friction to limit lateral movement of the bolster.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. A side frame comprising tension and compression members, a column adjacent each end of said frame and comprising spaced inboard and outboard webs merging at their lower and upper ends with said tension and compression members respectively, and a wall interconnecting said webs at one of their corresponding lateral edges at the lower ends thereof and merging with said tension member, said wall being bifurcated intermediate the ends of said column to form spaced legs defining an upwardly opening slot, diagonally disposed coplanar ledges on the adjacent sides of said webs formed integral therewith and connected at their lower ends to the upper ends of said legs, and spaced transverse webs on the other corresponding edges of said inboard and outboard webs and merging at their upper ends with said compression member and at their lower ends with the upper ends of said ledges.

2. In a railway car truck, a supporting member having a compression member and a column, a member spring-supported on said supporting member and having a vertical friction surface adjacent said column, a pocket in said column, a friction assembly in said pocket comprising a friction shoe having a front wall in substantially vertical face frictional engagement with said surface, wedge faces on said column at opposite sides of said shoe, wedge means at opposite sides of said shoe in wedge engagement with said wedge faces, a spring extending between said faces and positioned eccentrically of the shoe and bearing thereagainst and against said compression member, means for positioning said spring on said compression member comprising a lug formed thereon and engageable with one side of said spring, and spaced webs on said column at the opposite side of said spring.

3. In a railway car truck, a side frame having a pocket, a bolster spring-supported from said frame, wedge means on said frame in said pocket sloping toward said bolster, a friction shoe in said pocket and having vertically diverging front and rear walls, the former frictionally engaging said bolster, a bottom wall and spaced side walls interconnecting said front and rear walls, curved wedge surfaces on said side walls engaging said wedge means, and a spring extending into said shoe and seated at one end on said bottom wall and at its other end against said frame, the points of engagement of said surfaces with said wedge means and the axis of said spring lying in a plane extending transversely of the frame.

4. In a railway car truck, a column member, a relatively movable member supported adjacent thereto, friction means housed in one of said members, said means comprising a shoe, vertically spaced substantially parallel inclined walls on said shoe and said one member respectively, cooperating wedge surfaces on said shoe and said last-mentioned member intermediate said walls sloping toward the other member, and resilient means under compression between said walls, the points of engagement of said surfaces and the

axis of said resilient means lying in a plane extending transversely of the frame, said resilient means exerting a force substantially normal to said walls.

5. In a car truck, a support member, a supported member, a substantially vertical friction surface on one of said members, spaced wedge faces on the other of said members sloping toward said surface and disposed at an acute angle

10 with respect thereto, a friction element between said spaced wedge faces and having portions in wedge engagement therewith, an abutment surface on said element spaced vertically with respect to said faces and lying in a plane disposed at an obtuse angle with respect to said friction surface, an abutment surface on said other member spaced vertically from said first-named abutment surface and lying in a plane substantially parallel thereto, and resilient means extending between and reacting against said abutment surfaces.

6. In a truck, a side frame member, a bolster member spring-supported therefrom, facing converging surfaces on said members arranged at an acute included angle therebetween, a shoe wedged between said surfaces, spring means reacting between said shoe and one of said members for urging the shoe into the wedged position thereof, and complementary engageable faces on said shoe and one of said members and arranged with respect to the surface on the other member at an acute included angle of lesser magnitude than said included angle between said first-mentioned surfaces, those of said faces on the last-mentioned one of said members facing the surface on said other member and being engageable with those of said faces on the shoe upon movement of the shoe in a direction away from the surface on said other member to increase the resistance to said movement.

7. In a railway car truck, a side frame having a pocket, a bolster supported from said frame adjacent said pocket, and friction means in said pocket comprising a friction shoe having a front wall in frictional engagement with said bolster along a substantially vertical plane, flat wedge surfaces in said pocket sloping toward said bolster, a spring extending between said surfaces bearing against said shoe and said frame and spaced laterally of said front wall, and crowned wedge faces on said shoe arranged to engage said surfaces at points aligned with the axis of said spring transversely of said frame, said spring being oriented to deliver a force diagonally toward said bolster.

8. In a car truck, a side frame, a bolster supported therefrom, a friction shoe in said frame and having front and rear portions, said front portion frictionally engaging said bolster, cooperating wedge surfaces on said shoe and frame sloping toward the bolster, and a spring compressed between said frame and said shoe, said spring extending into said shoe adjacent said rear portion thereof, said surfaces engaging each other at points disposed in alignment with the axis of said spring transversely of said frame, said points being disposed closer to said rear portion than to said front portion of said shoe.

9. A railway car truck comprising a frame, a bolster spring-supported therefrom, spaced coplanar wedge surfaces on the frame sloping toward the bolster, a shoe extending between said surfaces and in wedge engagement therewith and in frictional engagement with the bolster, and a spring sloping downwardly toward the bolster,

the upper end of said spring bearing against the frame and the lower end of said spring bearing against said shoe, the engagement between said shoe and surfaces occurring in a plane containing the axis of said spring and extending transversely of said frame.

10. In a railway car truck, a side frame, a bolster spring-supported therefrom, a shoe pocketed in said frame and in frictional engagement with said bolster, a spring in said frame oriented to deliver a force diagonally toward said bolster and reacting between said shoe and said frame, and cooperating wedge surfaces on said frame and shoe engaged at points disposed with the axis of said spring in a plane extending transversely of the frame.
